UNITED STATES PATENT OFFICE.

JAMES KEESHEN, OF OKLAHOMA CITY, OKLAHOMA.

CERTIFICATE HOLDER.

Application filed July 30, 1925. Serial No. 47,066.

The object of this invention is to provide a simple, inexpensive device for holding a certificate of registration or similar card.

Another object is to provide a means of sealing the card to the holder.

Another object is to provide a means of sealing the card and holder to a permanent part of the automobile.

A still further object is to provide a means of sealing the various elements together without obscuring the card.

Other objects of the invention will appear from the following detailed description.

With this invention the owner of a motor vehicle can comply with a law now existing in some States requiring the owners of all motor vehicles to carry in a prominent place on the car a certificate of ownership. The law further requires that this certificate of ownership must be so attached that it cannot be removed without mutilation. By carrying a metal seal bearing the same number as that on the certificate this invention curbs the transfer of the certificate of ownership because this certificate cannot be removed from its container without either mutilating the certificate or the seal.

The form of the invention is shown in the accompanying drawing, of which Figure 1 is a plan view showing the several elements in assembled and sealed relation, while Figure 2 is a similar view showing the several parts unassembled. Figure 3 is a fragmentary cross section of an automobile dash board and the several elements of the invention illustrating the manner of attaching same to a vehicle. In Figure 1 is shown the metal certificate holder (1) with the seal (2), the certificate (3), the transparent cover (5), and the slotted holes (4) through the holder, the certificate and the transparent shield all parts being assembled.

In Figure 2 a view of the parts in unassembled relation is shown of which (1) is the metal holder, (2) is the certificate, (5) is the transparent shield. (2) is the seal which is threaded through the slots (4) in the holder and may be threaded through two corresponding slots in the instrument or dash board 6 of the car as shown in Figure 3 and finally sealed. This seal (3) can carry the name of the State, a number denoting a certain county in that State, the certificate number and a secret number or symbol belonging to the owner of the car. The printing on the certificate is no part of the pres-

ent invention. The invention of the seal itself is not claimed.

The holder is supported by means of screws 7 passing through holes 8 in the holder, to the dash board or other permanent part of the car, and the certificate being sealed in place over the screw heads and under the forwardly bent down edges will be mutilated by any tampering whatsoever with the screws.

Having thus clearly described my invention, I claim:

1. The combination with a permanent part of a vehicle of a certificate holder, a certificate fitting therein, and means, including a slot in one element adapted to register with a slot in each of the other elements, to ribbon and seal said certificate and holder together and to the permanent part of the vehicle.

2. The combination with a vehicle, of a certificate holder having turned down edges, a certificate fitting under said edges, and means including spaced registering slots in each element to ribbon and seal said certificate and holder together and to a permanent part of the vehicle.

3. A certificate holder, a certificate held therein and bearing identification marks, means for sealing said holder to a part of a vehicle, including spaced, registering slots in each element, said sealing means being also provided with identification marks in duplicate of those on the certificate.

4. The combination with a vehicle of a certificate holder and means to fasten said holder to a permanent part of said vehicle, a certificate fitting in said holder and over said fastening means, and means, including a slot in one element adapted to register with a slot in each of the other elements, to seal said certificate to the vehicle, arranged so that tampering with said fastening means will cause mutilation of the certificate or seal.

5. A card or certificate holder having spaced slots adapted for registry with similarly spaced slots in a support, a card having identification data fitting in said holder, and having slots adapted to register with said first mentioned slots, and a metal seal bearing duplicate identification data, ribboned through all of said slots, whereby removal of any element will cause mutilation of the card, or seal.

JAMES KEESHEN.
